United States Patent Office

Des. 187,245
Patented Feb. 16, 1960

187,245

CANTEEN

Lewis B. Thompson, Jr., Arlington, Mass., assignor to the United States of America as represented by the Secretary of the Army

Application August 24, 1959, Serial No. 57,266

Term of patent 14 years

(Cl. D58—8)

The essential features of my design are shown in full lines.

I claim:

The ornamental design for a canteen, substantially as shown and described.
